UNITED STATES PATENT OFFICE.

THOMAS M. NORTH, OF PLAINFIELD, NEW JERSEY, ASSIGNOR TO THE ALUMINUM PLATE AND PRESS COMPANY, OF PLAINFIELD, NEW JERSEY, AND NEW YORK, N. Y., A CORPORATION OF WEST VIRGINIA.

PLATE-CLAMPING DEVICE FOR PRINTING-PRESSES.

SPECIFICATION forming part of Letters Patent No. 695,414, dated March 11, 1902.

Application filed February 21, 1901. Serial No. 48,364. (No model.)

To all whom it may concern:

Be it known that I, THOMAS M. NORTH, a subject of the King of Great Britain and Ireland, residing at Plainfield, in the county of Union and State of New Jersey, have invented 5 certain new and useful Improvements in Plate-Clamping Devices for Printing Presses, of which the following is a specification.

My invention relates to improvements in sheet-clamping devices for printing-cylinders of printing-presses by which a sheet-metal printing-plate of aluminium, zinc, or other metal is secured in proper position upon the printing-cylinder. Many devices of this kind 10 have been produced, but with all such devices known to me the structures have been such that the edges of the printing-plate have to be pulled inwardly (and are more or less bent) over the edges of the plate-supporting 15 surface of the cylinder by the action of the clamps, which renders it difficult to exert a sufficient pull upon the different sections of a plate to equally strain it throughout its area, and when the plate is properly stretched or 20 strained it is frequently broken or injured along the bent edges. The old forms of plate-securing devices are also objectionable, because they require too much of the cylinder-surface to be cut away for their reception. 25 The object of my present invention is to provide a simple and effective plate straining and clamping device for printing-cylinders which will overcome the difficulties pointed out. To this end I provide the printing-cylinder of a press with sectional plate clamping 30 and straining rolls supported in suitable sockets at the edges of the plate-supporting surface of the cylinder and provided with means for engaging the edges of a printing-plate and 35 with means for rotating the roll-sections in their support for properly straining the plate. These improved plate straining and clamping devices roll the edges of the printing-plate upon them without abruptly bending or deflecting it and without any tendency to break 40 or otherwise injure the printing-plate. The construction is such that a minimum portion of the printing-cylinder is cut away, thereby leaving a larger part of the cylinder-surface

for the plate-receiving and ink-distributing 50 surfaces.

In order that my invention may be fully understood, I will first describe the same with reference to the accompanying drawings and afterward point out the novelty with more 55 particularity in the annexed claims.

In said drawings, Figure 1 is a detail front elevation of part of a printing-cylinder equipped with my improved plate straining and clamping devices. Fig. 2 is a transverse 60 sectional view of the same, taken on the line 2 2 of Fig. 1. Figs. 3, 4, 5, and 6 are enlarged detail sectional views of a part of a printing-cylinder, showing the improved plate straining and clamping devices, said views being 65 taken on the section-lines 3 3, 4 4, 5 5, and 6 6, respectively, of Fig. 1 and the plate-clamping roll being omitted in Fig. 6.

1 is a printing-cylinder of a printing-press having a plate-supporting surface 2 and an 70 ink-distributing surface 3, said surfaces 2 and 3 being separated by longitudinally-extending gaps or cavities in which are mounted the plate straining and clamping devices. The edges of the plate-supporting surface 2 are 75 beveled or rounded off, as shown at 4, to avoid abrupt edges for the printing-plate to be secured over.

Directly beneath the front and rear edges of the plate-supporting surface 2 are formed 80 the cylindrical sockets 5, cut out at one side, as shown at 6. These sockets 5 are adapted to receive and support the sections of the plate straining and clamping rolls 7, which are of cylindrical form of the proper size to fit snugly 85 in the sockets 5 and turn freely therein under the action of the turning devices, presently to be explained. A plurality of these plate straining and clamping roll sections 7 are mounted in each of the longitudinal sockets or pockets 5 of the printing-cylinder, the 90 number of the rolls 7 depending upon the length of the printing-cylinder and the required adjustment for the printing-plate.

Each of the clamping and straining roll 95 sections 7 has a longitudinally-extending angular recess or cavity 10 cut in its face, and fitting snugly in this angular cavity is a

clamping-bar 11, having a plate-engaging flange 12, which is shaped to fit snugly upon the curved surface of the clamping-roll section for securely clamping the edge of the 5 printing-plate P between it and the roll.

13 13 are threaded bolts passing through openings 14 in the clamping-plate 11 and threaded into sockets 15 of the clamping-roll sections. The bolts 13 are formed with collars 16, which engage in the recesses formed in the clamping-plate 11, and the squared heads 17, by which the bolts may be rotated in their seats.

Adjacent to the sockets or pockets 5 in the 15 plate-cylinder are formed the series of deep recesses or cavities 20 for the purpose of allowing room for the free movement of the clamping-plates 11 when the clamping-roll sections 7 are rotated in their supporting-sockets for 20 straining the printing-plate. These recesses 20 are separated by dividing walls or lugs 21, in which are cut the circular recesses 22.

23 is a worm-gear mounted upon a journal-bolt 24, which is journaled in the bearing 25 and secured in place by a washer 26 and nut 27. The worm-gear 23 rests in the circular socket 22 and is supported in mesh with a segment worm-gear 28, formed in one face of the clamping-roll section 7. The worm-gear 23 30 is provided with a squared wrench-engaging end 29, by which it may be rotated in its bearing. It will be observed that the rotation of the worm-gear 23 will cause the roll-section 7 to rotate slowly in its supporting-socket 5.

35 Each of the roll-sections 7 is provided with a segment worm-gear 28 adjacent to one of its ends, and each of these segment worm-gears is in constant mesh with the controlling and operating worm-gear 23, so that the 40 several roll-sections 7 may be independently rotated by means of a wrench or suitable key for straining the printing-plate throughout its area.

The roll-sections 7 are mounted end to end 45 in the supporting-socket 5 of the printing-cylinder and are held in place by the engagement of the worm-gears 23. The gears 23 fit snugly in their supporting-sockets 22 and are held thereby into working engagement with 50 the segment-gears on the clamping-roll sections. The cut-out portions 6 of the sockets 5 are less than half the circumference of the sockets in extent, so that there is no possibility of the sectional clamping-roll sections 55 being forced laterally out of their socket. The sectional rolls can be removed only through the open ends of the supporting-sockets.

It will be observed that with my improved plate straining and clamping device the 60 front and rear edges of the plate P are clamped to the sectional rolls at different points by means of the clamping-plates 11. The several sections of the rolls are then rotated in their bearings by the means described until 65 the printing-plate has been properly strained over the plate-supporting surface 2 of the cylinder. As the sections of the clamping-

roll are rotated for straining the printing-plate it will be observed that the plate will be rolled upon the clamping-roll over the 70 beveled or curved edges 4 of the plate-supporting surface of the cylinder, so that there will not be any abrupt bend or break in the plate. This arrangement also enables the operator to more effectively strain and stretch 75 the printing-plate over the cylinder by reason of the absence of abrupt edges, over which the plate must be drawn, it being perfectly clear that the plate will yield more readily to the straining action of the straining and clamping rollers than it would to the action of a clamping and straining device which pulls the edge of the plate down over an abrupt edge of the plate-supporting surface. The improved arrangement is therefore 80 more effective in operation and preserves the printing-plates better than other forms of clamping devices. The clamping-rolls are also of great value, because of the small proportion of the cylinder-surface utilized for 85 their reception. With my improved clamping devices I am able to utilize a much larger proportion of the cylinder-surface for the reception of the printing-plate than with any other clamping device known to me. 90

Having thus described my invention, the following is what I claim as new therein and desire to secure by Letters Patent:

1. The combination of a printing-cylinder having a plate-supporting surface, a plurality 100 of independent plate straining and clamping rolls arranged end to end and journaled in the cylinder adjacent to the edge of the plate-supporting surface, independent means upon the several straining and clamping rolls for 105 engaging the edge of the printing-plate, and independent means for rotating each of the rolls in its bearing, substantially as set forth.

2. The combination of a printing-cylinder having a plate-supporting surface and a roll-supporting socket adjacent to one edge of the plate-supporting surface, with a plate straining and clamping roll journaled in said socket and provided with means for rotating it, and means for clamping the edge of a printing-plate to the roll, said roll-supporting socket in the cylinder having a longitudinal opening or cut-out portion of less than half the circumference of the socket so as to inclose more than half the circumference of the roll, 115 substantially as and for the purpose set forth.

3. The combination of a printing-cylinder having a plate-supporting surface and a roll-supporting socket adjacent to one edge of the plate-supporting surface, a plurality of plate 125 straining and clamping rolls journaled in said socket, each of the said rolls being provided with a segment-gear and with a plate-clamping device, a series of independent operating-gears journaled in the printing-cylinder and supported in mesh with the several segment-gears of the rolls, substantially as set forth. 130

4. The combination of a printing-cylinder having a plate-supporting surface and a roll-

supporting socket adjacent to one edge of the plate-supporting surface, a plurality of plate straining and clamping rolls journaled in said roll-supporting socket, a segment-gear upon each roll, a plate-clamp mounted upon each roll, recesses or pockets formed in the printing-cylinder adjacent to and parallel with the roll-supporting socket for the reception of the plate-clamps when the rolls are rotated, di-

viding lugs or walls separating said clamp-receiving recesses or pockets, and independent operating-gears journaled in said dividing lugs or walls and engaging the segment-gears of the rolls, substantially as set forth.
